UNITED STATES PATENT OFFICE.

HENRY T. WELCH, OF SAN JOSÉ, CALIFORNIA.

VETERINARY INHALER.

SPECIFICATION forming part of Letters Patent No. 451,655, dated May 5, 1891.

Application filed September 5, 1890. Serial No. 364,075. (No model.)

To all whom it may concern:

Be it known that I, HENRY T. WELCH, a citizen of the United States, residing at San José, Santa Clara county, State of California, 5 have invented an Improvement in Inhalers; and I hereby declare the following to be a full, clear, and exact description of the same.

My invention relates to inhalers; and it consists in the novel construction hereinafter fully 10 described, and specifically pointed out in the claims.

The object of my invention is to provide an inhaler which is specially adapted for horses, and which by reason of its construction can 15 be readily and securely applied in a way that will not inconvenience or worry the horse.

Referring to the accompanying drawings for a more complete explanation of my invention, Figure 1 is a view showing the application 20 of my inhaler. Fig. 2 is a perspective view of the inhaler.

A is a hollow receptacle bent to conform substantially to the curve of the horse's upper lip. Its ends are covered by screw-caps B, 25 which can be readily removed and easily replaced. The hollow receptacle is provided with a number of holes a, distributed over its upper portion in any suitable manner and number.

30 C is a cross-strap fitted upon the hollow receptacle by means of loops c, and D is a front strap, the upper end of which is secured to the cross-strap and the lower end is fitted to the hollow receptacle by a loop d.

35 E are side straps secured to the ends of the cross-strap, and are used for attaching the inhaler to the bridle, halter, or other head-gear of the horse.

The medicinal preparation the vapor of 40 which is to be inhaled is put into the hollow receptacle at either end by removing the cap B, and when in the cap is to be replaced. If desired, some absorbent material may be put in the receptacle, so as to carry the medicine.

45 The inhaler is fitted to the horse, as shown, by the hollow receptacle passing about the upper lip of the horse directly under his nostrils. The cross-strap C runs across the nose of the horse above the nostrils, while the 50 front strap D passes down between the nos-

trils. The side straps E are run up and secured to the nose-strap of the halter or to any other portion of the head-gear of the horse. Thus the inhaler is well held to place, hanging under the nostrils of the horse, in which position it will not be disturbed or from which it cannot be removed by any rubbing of the horse or effort to dislodge it, as it will hang in proper place.

The receptacle is made, preferably, of a 60 metal tube, so that there is no danger of breaking it. It can be easily removed and disconnected from the straps by taking off the end caps and slipping the loops of the straps off over its ends, so that said receptacle can 65 be thoroughly cleansed.

Having thus described my invention, what I claim as new, and desire to secure by Letters Patent, is—

1. An inhaler for horses, consisting of a hollow medicine-receptacle having top perforations and bent to fit the upper lip of the horse below the nostrils, substantially as herein described.

2. An inhaler for horses, consisting of the 75 hollow medicine-receptacle having screw-capped ends and top perforations, and suitable straps to hold said receptacle in place under the nostrils of the horse, substantially as herein described.

3. An inhaler for horses, consisting of the curved hollow medicine-receptacle having the top perforations, the cross-strap connected with said receptacle, and the front strap connected with said receptacle and with the cross- 85 strap, substantially as herein described.

4. An inhaler for horses, consisting of the curved hollow receptacle provided with top perforations, the cross-strap and front strap fitted to said receptacle by sliding loops, 90 whereby they can be removed, and the side straps for connecting the receptacle with the head-gear of the horse, substantially as herein described.

In witness whereof I have hereunto set my 95 hand.

HENRY T. WELCH.
